UNITED STATES PATENT OFFICE.

NICOLAS GYMAITIS, OF SANTA BARBARA, CALIFORNIA.

FLUSH-VALVE MECHANISM.

Application filed March 1, 1922, Serial No. 540,311.

To all whom it may concern:

Be it known that I, NICOLAS GYMAITIS, a subject of the King of Greece, residing at Santa Barbara, in the county of Santa Barbara and State of California, have invented new and useful Improvements in Flush-Valve Mechanism, of which the following is a specification.

My invention relates to flush valve mechanism for toilets, and a purpose of my invention is the provision of a flush valve mechanism of extremely simple and durable construction which eliminates the necessity of employing a flush tank, and which when actuated operates to automatically discharge a predetermined quantity of water into the bowl.

Although I will describe only one form of flush valve mechanism embodying my invention and point out the novel features thereof in claims, it is to be understood that various changes and modifications may be made herein without departing from the spirit and scope of such claims.

25 In the accompanying drawings,

Fig. 1 is an enlarged vertical sectional view of the valve mechanism shown in the preceding figures.

Fig. 2 is an enlarged fragmentary sectional view of the valve cap comprised in the mechanism shown in Fig. 1.

Fig. 3 is a view showing the valve cap in side elevation.

Figs. 4 and 5 are transverse sectional views taken on the lines 4—4 and 5—5, respectively, of Fig. 1.

Similar reference characters refer to similar parts in each of the several views.

Referring specifically to the drawings my invention, in its present embodiment, comprises a tubular casing K threadedly engaging a casting C at a point indicated at 15. The casting C includes a depending extension 16 which provides a water receiving chamber having one end closed by a screw plug 17, while the other end is provided with a collar 18 which is threadedly engaged by a water supply pipe P. The main body of the casting C is formed with a conical port 19 which communicates with the chamber at its lower end and with a duct 20 at its upper end. The duct 20 communicates with a pipe extension 21 to which a pipe 22 is adapted to be connected for supplying water to the bowl. The port 19 is controlled by a valve V preferably formed of

rubber and of conical formation. This valve V is sustained upon a stem 23 slidably fitted in a suitable opening formed in the casting C and in an extension 24 provided on the upper end of the casting and extending into the casing K.

As clearly shown in Fig. 1, the stem 23 is extended above the extension 24 with its upper end provided with a plunger or piston 25 grooved to receive a packing ring 26 and adapted to slidably fit within casing K. Formed integral with or secured to the piston 25 is a sleeve 27 which as clearly shown in Fig. 4, is of cylindrical form and is provided at regular intervals on its periphery with longitudinally extending ribs 28 adapted to contact with the inner wall of the casing K. This sleeve 27 is designed for the purpose of housing a coiled expandable spring 29 interposed between the piston 25 and the upper end of the extension 24 so as to normally urge the piston upwardly and to thereby close the valve V. A stuffing box 30 embraces the stem 23 at the upper end of the extension 24 for preventing the leakage of water upwardly around the stem.

For actuating the piston 25 and consequently the valve V, a rod 31 is fixed to the sleeve 27 so as to extend through a slot 32 formed in the casing K, such rod being provided with a handle 33 by means of which the sleeve may be moved downwardly against the tension of the spring 29 for moving the valve V to open position.

Removably associated with the upper end of the casing K is a closure plate 34 provided axially with an opening 35. Surrounding the opening and formed on the upper side of the plate 34 is a valve cap 36 which, as clearly shown in Fig. 2, is formed with an air intake port 37 and air exhaust ports 38. A ball check valve 39 controls the intake port 37 and is removably associated therewith by means of a plug 40. A valve 41 controls the exhaust ports 38, and this valve is adjustable by means of a stem 42 to control the passage of air through such ports. A hood 43 is detachably associated with the casing K, and this hood is formed with ports 44 through which air is admitted to or discharged from the ports 37 and 38.

In operation, the valve V normally occupies closed position with respect to the port 19 under the action of the spring 29

so that the passage of water from the duct 20 to the bowl is prevented. When supplying water to the bowl, the handle 33 is gripped and pushed downwardly to the 5 lower end of the slot 32 thereby imparting a corresponding movement to the piston 25 and all against the action of the spring 29. With the piston 25 in depressed position the valve 5 is moved downwardly from 10 the port 19 thereby opening the latter and allowing the passage of water from the pipe P through the port 19 and duct 20 to the pipe 22. During a downward movement of the piston 25, a suction is created in the 15 casing K above the piston thereby causing an influx of air through the ports 44 and 37 and finally into the casing through the opening 35. It will thus be seen that with the piston 25 in its lowermost position that 20 part of the casing above the piston is filled with a column of air. Naturally when downward pressure upon the handle is removed the spring 29 will expand to force the piston 25 upwardly but against the action 25 of the column of air within the casing as the latter is trapped within the casing by virtue of the check valve 39. The escape of air from the casing takes place through the ports 38 and by proper adjustment of 30 the valve 41, it will be clear that the discharge of air from the casing can be so restricted as to retard the upward movement of the piston 25 sufficiently to postpone the closing of the valve V.

35 In practice, the adjustment of the valve 41 is such that the valve V is maintained in open position for an interval sufficiently long to permit of the proper amount of water being supplied to the bowl.

40 What I claim is:

1. A flush valve mechanism comprising a casting, a casing supported on the casting, a port formed in the casting, a valve controlling said port, a stem formed on the valve 45 and slideable through the casting, a piston within the casing and connected to said stem, a sleeve fixed to the piston and having spacing ribs formed on the periphery thereof, a spring for normally urging the piston to a position in which said valve is closed, a handle extending through a slot in the casing and rigidly connected to the sleeve for moving the piston against the action of said spring to open said valve, and means for 50 controlling the flow of air to and from the casing.

2. A flush valve mechanism comprising a casting having a port formed therein, a

cylinder sustained on the casting, a piston movable within the cylinder, a sleeve fixed 60 to the piston and having spacing ribs formed on the periphery thereof, a stem for said valve slideable in the casting and connected to said piston, a spring within the sleeve and interposed between said piston and said casting for urging the piston to one end of the cylinder, a handle connected to said sleeve for manually moving the sleeve and piston against the action of said spring to open said valve, and valves for controlling 65 the influx and efflux of air into and out of the cylinder in a manner to retard the movement of the piston in the direction in which it is urged.

3. A flush valve mechanism comprising a 70 casting having a port formed therein, a cylinder sustained on the casting, a piston movable within the cylinder, a sleeve fixed to the piston, a stem for said valve slideable in the casting and connected to said piston, a spring within the sleeve and interposed 75 between said piston and said casting for urging the piston to one end of the cylinder, a handle connected to said sleeve for manually moving the sleeve and piston against 80 the action of said spring to open said valve, a plate closing one end of the cylinder having an opening formed therein, a valve cap formed in the plate and having intake and 85 discharge ports formed therein, a check 90 valve controlling the intake port, and a valve controlling the discharge port for the purpose described.

4. A flush valve mechanism comprising a casting having a port formed therein, a cylinder sustained on the casting, a piston movable within the cylinder, a sleeve fixed to the piston and having spacing ribs formed 95 on the periphery thereof, a stem for said valve slideable in the casting and connected 100 to said piston, a spring within the sleeve and interposed between said piston and said casting for urging the piston to one end of the cylinder, a handle connected to said sleeve for manually moving the sleeve and piston 105 against the action of said spring to open said valve, a plate closing one end of the cylinder having an opening formed therein, a valve cap formed in the plate and having intake and discharge ports formed therein, a 110 check valve controlling the intake port, and a manually adjustable valve controlling the discharge port.

In testimony whereof I have signed my name to this specification.

NICOLAS GYMNAITIS.
